THERMAL SWITCHING DEVICE

Hans H. Willmann, Berlin-Charlottenburg, Germany, assignor to Westinghouse Electric & Manufacturing Company, East Pittsburgh, Pa., a corporation of Pennsylvania

Application August 25, 1938, Serial No. 226,640
In Germany September 24, 1937

16 Claims. (CL. 60—23)

The invention relates to thermally responsive control devices in general and more particularly to thermal switching devices having bimetal control elements.

Thermal switching devices of the type having a bimetal strip supported between two bearing points have not proved entirely satisfactory due to the fact that the bimetal strip falls out of its bearing when the strip flexes more than a limited amount and also when the adjustable bearing is moved too great an amount. Such arrangements also require a very accurate maintenance of the length of the bimetal strips and of the distance between the bearing points during the manufacture and assembly of the devices.

One object of the invention is the provision of a thermal switching device having an improved bearing means for supporting the bimetal strip which prevents the strip from falling out of its bearings.

Another object of the invention is the provision of a thermal switching device having an improved bearing means for the bimetal element which permits maximum flexing and adjustment of the element and at the same time prevents the bimetal element from falling out of its bearings.

In accordance with the above objects of the invention, the bimetal strip either alone or with a separate heating strip therefor, is supported at its ends between two bearing means, one of which has a resilient construction to produce a resilient force on the end of the strip in the direction of its longitudinal axis. The other bearing is adjustable in a direction perpendicular to the longitudinal axis of the bimetal strip to adjust the control characteristic of the device.

While there are few difficulties in constructing thermal switching devices which operate reliably in the case of relatively large currents, rather substantial difficulties arise at lower currents, for example at the order of one ampere or less, since the amount of heat available for heating the bimetal element is relatively small. Because the amount of heat available is small, it has been the usual practice to heat the bimetal element indirectly by a heater strip or resistance which is electrically insulated from the bimetal strip by a sheet of mica. The mica sheet, however, is not a very good heat conductor and it does not permit sufficient heat to reach the bimetal element in the case of either high or low currents.

Another object of the invention is the provision of a thermal switching device having a bimetal strip and an electrical heating resistance

therefor, with an improved means interposed between the bimetal strip and the resistance which electrically insulates the heating resistance, and which at the same time effectively conducts heat from the resistance to the bimetal element.

According to the preferred embodiment of the invention the above object is carried out by providing an aluminum strip having oxidized surfaces, between the heating resistance and the bimetal strip. The aluminum strip serves to effectively conduct heat from the resistance to the bimetal strip. The oxidized surfaces are heat conducting, and also have a high dielectric strength so that they serve to electrically insulate the heating resistance from the aluminum strip and from the bimetal strip. The time constants or control characteristics of the device may be readily varied by providing a plurality of thin aluminum strips, in lieu of one thick strip, between the heating resistance and the bimetal strip.

The novel features that are considered characteristic of the invention are set forth in particular in the appended claims. The invention itself, however, both as to structure and operation together with additional objects and advantages thereof will be best understood from the following detailed description of several preferred embodiments thereof when read in connection with the accompanying drawing, in which:

Fig. 1 is a side elevational view of a thermal switching device of a type that has heretofore been known and used.

Fig. 2 is a side elevational view of a thermal switching device constructed in accordance with the present invention.

Fig. 3 is an end elevational view of the resilient bearing means shown in Fig. 2 which supports one end of the bimetal strip.

Fig. 4 is a plan view of the bimetal strip of the device shown in Fig. 2.

Fig. 5 is an enlarged fragmentary sectional view showing a preferred form of the thermally responsive control unit of the invention.

Fig. 6 is a plan view of the bimetal strip.

Fig. 7 is a plan view of the aluminum strip of the device shown in Fig. 5.

Fig. 8 is a plan view of the electrical heating resistance of the device shown in Fig. 5.

Fig. 9 is a plan view of the heat insulating strip used in the device shown in Fig. 5.

Fig. 10 is a plan view of the supporting strap

for engaging the free end of the heat insulating strap, and

Fig. 11 is a fragmentary sectional view similar to Fig. 5 showing a slightly modified form of the device.

Referring to Fig. 1 of the drawing which shows one type of thermal switching device, 1 is a bimetal strip which is supported at its ends in the indentation 2 of a rigid bearing bracket 3, and in the indentation 4 of an adjustable bearing 5. The bearing 5 is guided by a bracket 6 end is adjustable vertically by means of a screw 7. It is apparent that in the above construction when the bimetal strip flexes more than a limited amount, or when the adjustable bearing 5 is moved too far either upwardly or downwardly, the bimetal strip may fall out of its bearings.

The above described fault is avoided by the construction of the present invention illustrated in Figs. 2, 3, 4 and 5. Referring to these figures, 8 is 20 a base of insulating material on which is mounted a pair of rigid bearing brackets 9 and 10. An insulating bridge 11 connects the upper ends of the brackets 9 and 10 and serves to maintain them at a constant distance from each other.

An adjustable bearing 12 is threaded on an adjusting screw 13 which is vertically mounted on the bracket 10. The bracket 10 serves to guide the bearing 12 as it is moved vertically by the adjusting screw 13.

A bimetal strip 14 is supported at one end in a notch 15 formed in the adjustable bearing 12. The other end of the bimetal strip is notched at 16 (Fig. 4) and this end is supported by a resilient bearing 17 comprising a spring clip which has its lower end rigidly secured to the foot of the bracket 9.

The spring clip 17 has a reduced upper end 18 (Fig. 3) forming a pair of shoulders 19 for supporting the bifurcate ends 20 of the bimetal strip 14. The reduced portion 18 of the spring clip engages in the notch 16 of the bimetal strip, and the upper end of the spring clip is bent inwardly at 21 to prevent upward displacement of the end of the bimetal strip 14. The shoulders 19 prevent downward displacement of the strip 14.

The resilient spring clip 17 produces a resilient force on the end of the bimetal strip 14 in the direction of the longitudinal axis of the strip and thus prevents the bimetal strip from falling out of its bearings even when the strip 14 flexes its maximum amount, or when the bearing 12 is moved upwardly or downwardly to the limits of its movement.

A pair of resilient or flexible conducting terminal straps 22 and 23 serve to connect the ends of the bimetal strip 14 in an electrical circuit.

The above described device may be used to control circuit breakers, switches, or any pair of electrical contacts in a manner well known in the art. When the bimetal strip is heated a predetermined amount by the passage of an electrical current, the strip flexes, and this flexing movement is used to control a pair of contacts, or to release a circuit breaker mechanism to cause opening of the breaker. The control or trip characteristic of the device is adjusted by vertically moving the adjustable bearing 12 to change the position of the bimetal strip 14 with relation to the contacts, or releasing mechanism which it controls.

According to one embodiment of the invention, the bimetal strip 14 is preferably heated indirectly by a separate heating resistance in order that it may be heated a sufficient amount in response

to lower magnitude currents of predetermined value and duration. Referring to Figs. 5 through 10, the bimetal strip 14 is supported between two bearing points in the manner previously described, by the spring clip 17 and the adjustable bearing 12. The heating of the bimetal strip 14 is effected by means of a heating resistance strip 25. The strip 25 consists of any suitable resistance material such as a nickel-chromium or other alloy, and preferably has a sinuous or zigzag form as shown in Fig. 8.

A heat conducting and electrical insulating strip 26 is interposed between the heating resistance 25 and the bimetal strip 14 for the purpose of conducting heat from the resistance 25 to the bimetal strip 14 and for electrically insulating the heating resistance from the bimetal strip. According to the preferred embodiment of the invention, the strip 26 is composed of aluminum, either in pure or alloy form, which is a good heat conducting material. The surfaces of the aluminum strip 26 are oxidized galvanically, or in any other suitable manner. The oxidized surfaces of the aluminum strip have a high dielectric strength and serve to electrically insulate the heating resistance 25 from the aluminum strip 26 and from the bimetal strip 14. The oxidized surfaces of the aluminum strip while having a high dielectric strength are also good heat conductors so that an efficient heat transfer from the heating resistance 25 to the bimetal strip 14 is attained even on small currents. The strip 26 may be composed of other materials providing the material is a good heat conductor and has a very thin coating of an electrical insulator. Alloys of aluminum and magnesium with an oxide coating may be used. While oxidized aluminum has the advantage that it is a very good insulator against substantial voltages, other materials such as copper with an oxide coating on each side may be used where it is only necessary to insulate against lower voltages.

The heating resistance 25 is preferably covered on its side opposite the bimetal strip 14, by a strip 27 of suitable heat insulating material such as hard paper.

If desired, a plurality of thin aluminum strips (Figs. 11), in lieu of the one strip, may be interposed between the heating resistance 25 and the bimetal strip 14, for the purpose of introducing or varying the time constant of the device. By using a plurality of thin strips of aluminum in place of a single thicker strip, the flexing of the thermally responsive control unit is not interfered with. The time constant of the device may be varied by using strips 26, or composite strips, of different thickness between the heating strip and the bimetal strip.

The bimetal strip 14, the aluminum strip 26, the heating resistance 25, and the heat insulating strip 27 are united together by means of a pair of rivets 28 and 29 to form a single unit which is supported between the two bearings 12 and 17. To avoid any hindrance of flexing movement of the bimetal strip 14, the aluminum strip 26 is secured only at one end by the rivet 29, its free end terminating short of the secured ends of the other strips. Similarly, the heat insulating strip is secured at one end only by the rivet 28, its other end terminating short of the secured ends of the other strips. The heating resistance strip 25 is resilient due to its zigzag form and may therefore be secured at each end by the rivets 28 and 29 without interfering with the bending of the bimetal strip.

The rivet 29 is enclosed in an insulating bushing 30 to insulate the bimetal strip 14 and the aluminum strip 26 from the current connection 23 which is electrically connected by the rivet 28 to one end of the heating resistance 25. The other end of the heating resistance 25 is electrically connected to the current connection 22 by means of the rivet 28.

A strap 32 secured by the rivet 29, has an offset end which engages under the right hand free end of the heat insulating strip 27 to support this end of the heat insulating strip 27.

A spacer element 33 of the same thickness as the strip or composite strips 26 is interposed between the left-hand ends of the heater strip 25 and the bimetal strip 14 beyond the free end of the strip or strips 26.

The conductors 22 and 23 constitute the terminals of the device and serve to electrically connect the heater strip 25 in the electric circuit. It will be noted that the heater strip 25 is electrically insulated from the bimetal strip 14 by the oxidized surfaces of the aluminum strip 26, and by the insulating bushing 30. The terminal conductor 23 which is connected to the right-hand end of the heater strip 25 need not be secured directly to the bracket 10. If, however, the terminal conductor is secured to the supporting bracket 10, it is electrically insulated therefrom in any suitable manner, as by an insulating washer and bushing (not shown). However, the bearing block 12 may be composed of insulating material in which case no insulation is necessary between the terminal 23 and the bracket 6.

While the invention has been disclosed in accordance with the provisions of the patent statutes, it is to be understood that various changes in the structural details of the device may be made without departing from the spirit of the invention.

The invention claimed is as follows:

1. In a thermal control device, a thermally responsive control element, an electrical heating resistance disposed adjacent said element for heating said element, and a metallic member of good heat conducting material interposed between the heating resistance and the control element for conducting heat from said resistance to said element, said conducting member having a surface which conducts heat from said resistance to said element and which also electrically insulates said element from said heating resistance, said surface on opposite sides of said metallic member being disposed in contact with said heating resistance and said thermally responsive control element.

2. In a thermal control device, a control element of bimetallic material, an electrical heating resistance disposed adjacent said element for heating said element, and a metal member of good heat conducting material interposed between said element and said resistance for conducting heat from said resistance to said element, said conducting member having a surface composed of a material which conducts heat from said resistance to said element, and which electrically insulates said heating resistance from said control element, the said surface of said member being disposed in contact with said heating resistance and said bimetallic control element.

3. In a thermal control device, a thermal element, an electrical heating resistance disposed adjacent said element for heating said element, and an aluminum strip having an oxidized surface, interposed between said element and said

heating resistance and in contact with each for conducting heat from said resistance to said element.

4. In a thermal control device, a thermal element, an electrical heating resistance disposed adjacent said element for heating said element, and an aluminum strip interposed between said element and said heating resistance for conducting heat from said resistance to said element, said strip having oxidized surfaces in contact with said heating resistance and said thermal element.

5. In a thermal control device, a control element of bimetallic material, an electrical heating resistance disposed adjacent said element for heating said element, and an aluminum strip interposed between said element and said resistance, said strip having oxidized surfaces in contact with said bimetallic element and said electrical heating resistance which serve to electrically insulate said resistance from said strip and said element and which also conduct heat from said resistance to said element.

6. In a thermal switching device, a thermal trip element comprising a strip of bimetallic material, an electrical heating resistance disposed adjacent and parallel to said bimetal strip, and an aluminum strip having an oxidized surface interposed between said bimetal strip and said heating resistance and having its surface in contact with each for conducting heat from said resistance to said bimetal strip, said oxidized surface serving to electrically insulate said resistance from said aluminum strip and said bimetal strip and also serving to conduct heat from said resistance to said bimetal strip.

7. In a thermal control device, a thermal element, an electrical heating resistance disposed adjacent to said element for heating said element, and a composite member comprising a plurality of thin metallic conducting strips interposed between said heating resistance and said element for conducting heat from said resistance to said element, and at least one of the surfaces of at least one of the strips of said composite member having a thin coating to electrically insulate said heating resistance from said strips and said element and to conduct heat from said heating resistance to said element.

8. In a thermal switching device, a bimetallic strip, an electrical heating resistance disposed adjacent and parallel to said bimetal strip for heating said bimetal strip, and an aluminum strip having oxidized surfaces, interposed between said bimetal strip and said heating resistance, and means securing said bimetal strip, said aluminum strip and said heating resistance together and in contact at one end.

9. In a thermal switching device, a bimetallic strip, an electrical heating resistance disposed adjacent and parallel to said bimetal strip for heating said bimetal strip, and a strip of conducting material having an insulating surface, interposed between said bimetal strip and said heating resistance, means for rigidly mechanically connecting said bimetal strip and said conducting strip in contact together at one end, and the other end of said conducting strip being movable relative to the other end of said bimetal strip.

10. In a thermal switching device, a bimetallic strip, an electrical heating resistance disposed parallel to and adjacent said bimetal strip for heating said bimetal strip, a strip of conducting material having a very thin electrically insulating surface, interposed between said heating resistance and said bimetal strip and disposed with

its insulating surface in contact with each for conducting heat from said heating resistance to said bimetal strip, and a strip of heat insulating material on the side of said heating resistance opposite the bimetal strip.

11. In a thermal switching device, a bimetallic strip, an electrical heating resistance disposed parallel to and adjacent said bimetal strip for heating said bimetal strip, an aluminum strip having oxidized surfaces, interposed between said heating resistance and said bimetal strip for conducting heat from said heating resistance to said bimetal strip, and a strip of heat insulating material on the side of said heating resistance opposite the bimetal strip, means rigidly mechanically connecting said bimetal strip, said heating resistance and said heat insulating strip together at one end, and means rigidly mechanically connecting only the other ends of said bimetal strip and said heating resistance together with one end of said aluminum strip, said last mentioned mechanical connection including a clamping strap for engaging the free end of said heat insulating strip to hold said end of said strip in position against said heating resistance.

12. In a thermal switching device, a strip of bimetallic material, an electrical heating resistance for heating said strip, an aluminum strip having oxidized surfaces, interposed between said resistance and said bimetal strip for conducting heat from said resistance to said bimetal strip, means mechanically securing said elements together to form a unit and a pair of spaced bearing means engaging the ends of said unit for supporting said unit, at least one of said bearing means being resiliently mounted to produce a resilient force on the end of said unit acting in the direction of the longitudinal axis of the unit, and means for adjusting the position of one of said bearing means in a direction substantially perpendicular to the longitudinal axis of the bimetallic strip.

13. In a thermal control device, a strip of bimetallic material, a pair of spaced bearing means engaging the ends of said strip for supporting said strip, at least one of said bearing means having a resilient construction for producing a resilient force on the end of said strip in the direc-

tion of the longitudinal axis of said strip to prevent said bimetal strip from falling out of its bearings, said force being insufficient to produce any substantial flexing of said bimetal strip and offering no substantial resistance to the bending of said strip when the strip is heated.

14. In a thermal control device, a strip of bimetallic material, supporting means for said strip comprising a rigid bearing having a notch in which one end of said strip is engaged, and a resilient bearing means engaging the other end of said strip for producing a resilient force on the end of said strip in the direction of the longitudinal axis of said strip to prevent said bimetal strip from falling out of its bearings, said strip when heated in response to predetermined conditions moving relatively slowly throughout its range of movement.

15. In a trip device, a strip of bimetallic material, a pair of spaced bearing means engaging the ends of said strip for supporting said strip, one of said bearing means being adjustable in a direction perpendicular to the longitudinal axis of the strip for varying the trip characteristic of the device, and the other of said bearing means having a resilient construction for producing a resilient force on the end of said strip in the direction of the longitudinal axis of said strip toward said adjustable bearing means.

16. In a thermal switching device, a strip of bimetallic material having a notch in one end thereof, a bearing engaging the end of said strip opposite the notched end and a resilient bearing engaging the notched end of said strip for producing a resilient force on the end of said strip in the direction of the longitudinal axis of the strip, to prevent said bimetal strip from falling out of its bearings, said force being insufficient to produce any substantial flexing of said bimetal strip and offering no substantial resistance to the bending of said strip when the strip is heated, said resilient bearing comprising a spring clip having a reduced end portion engaged in said notch and an inwardly bent end on the reduced portion for preventing lateral displacement of the notched end of said strip.

HANS H. WILLMANN.
